UNITED STATES PATENT OFFICE.

JOHN JOSEPH HOGAN, OF PLAINFIELD, NEW JERSEY.

INTERNAL-COMBUSTION ENGINE.

Application filed July 8, 1921. Serial No. 483,181.

To all whom it may concern:

Be it known that I, JOHN JOSEPH HOGAN, a citizen of the United States of America, residing at Plainfield, New Jersey, have invented a new and useful Internal-Combustion Engine, of which the following is a specification.

My invention relates to new and useful improvements in internal combustion engines. It is of particular utility when employed with an engine of the two-cycle multiple-cylinder type. In such engines difficulty is experienced in adequately and properly charging the cylinders with an effective mixture of air and fuel. By my improvement this charging of the cylinders is most effectively accomplished and the efficiency of the motor is correspondingly increased.

20 In the accompanying drawings:

Fig. 1 is a vertical cross sectional view.

Fig. 2 is a side elevation partly in section.

Figs. 3, 4, 5 and 6 are vertical cross sectional views respectively showing the parts in different positions to facilitate an understanding of the full cycle of operation.

In the drawings, I have shown my invention in a preferred form, the views, however, being conventional in many respects, it being understood that it is my chief purpose herein to make clear the principle of operation without regard to exact dimensions.

1—1 represent two cylinders mounted upon a suitable base 2 (Fig. 2), which is broken away at the left hand end to indicate that the length of the base may be increased whereby the engine may have any desired number of cylinders.

Since each cylinder corresponds mechanically I will describe the various parts of only one. Referring to Fig. 1, it will be seen that the cylinder is of the differential type, that is to say, the upper part of the cylinder is of smaller internal diameter than the lower part. The upper chamber in said cylinder constitutes the working chamber while the lower chamber constitutes what I will term the pumping or compression chamber. Mounted in the cylinder is a piston 3. The upper part of this piston fits the bore of the working chamber, while the lower part is of larger diameter and fits the bore of the pumping chamber. The displacement of the piston in the pumping chamber is preferably greater than the ca-

pacity of the working chamber. 4 represents the crank shaft of the engine, 5 the crank and 6 the connecting rod between the piston 3 and the crank 5. 7 represents a spark plug which constitutes one suitable means for securing ignition. 8 represents a valve casing. 9 represents a rotary valve mounted within said casing and driven in any suitable way from the shaft 4, as for example, by a chain 10 mounted on suitable sprockets. In the form shown, the valve 8 makes one turn to two turns of the shaft 4. 11 represents an exhaust port in the cylinder wall at the lower end of the working chamber. This exhaust port is controlled by the piston 3 which acts as a valve therefor. The valve 9 has a cross port therethrough from side to side. 12 represents a portion of the manifold pipe through which gas is supplied from a suitable source to the several cylinders of the engine. 13 represents an intake port leading into the upper end of the working chamber. 14—15 are ports in the wall of the valve casing. 16 is a passage-way leading from the pumping chamber to the ports 14—15. The manifold pipe 12 communicates with a passage or port 17 which also leads to the valve 9. The inner end of the port 17 is enlarged or extended as indicated at 17^a for the purpose hereinafter described.

Having now referred to the various parts of the engine, I will describe its operation throughout one complete cycle. In Fig. 3, the piston 3 is indicated as on its downward or power stroke. When it is in the position shown, the valve 9 closes the inlet port 13, and the piston itself closes the exhaust port 11. As the piston proceeds downwardly the valve 9 turns in the direction of the arrow. On this working stroke the lower enlarged end of the piston is creating suction within the pumping chamber and is drawing gas thereinto since the cross-port through the valve 9 at this time is opening communication between the ports 17—14. When the piston nearly reaches the lower end of its downward stroke, it uncovers the exhaust port 11 and the burnt gases are permitted to escape therethrough. When the piston reaches the limit of its downward stroke (as shown in Fig. 4), the valve 9 will have been turned sufficiently to close the passage therethrough from port 17 to 14.

On the up stroke of the piston (indicated

in Fig. 5), the piston 3 first closes the exhaust port 11, and when said port is fully closed the cross-port through the valve 9 will begin to open the ports 15—13 so that gas 5 then being compressed in the pumping chamber may be forced from said chamber through said ports and into the working chamber against the ascending piston. This continues until the piston reaches a predetermined elevation, at which time, as shown 10 in Fig. 6, the cross-port through valve 9 will connect the port 14 with the part 17^a of port 17 so that for the balance of the upward stroke of the piston a substantial part of the compressed gas in the pumping cylinder 15 will be forced into the manifold 12 to be utilized by one of the other cylinders of the engine then taking, or about to take, gas. It is well understood that a mixture of air and 20 gasoline, under compression is more effective than when uncompressed. It follows therefore that to discharge even a relatively small amount of effective mixture into the manifold will have the effect of improving the character of the gas therein, and to that extent will improve the aforesaid functioning of the motor. When the piston reaches the extreme limit of its upward stroke the ports 14—17 will be in practically wide open communication and will remain open until the piston again reaches approximately the limit of its down stroke, when they will be again closed as shown in Fig. 4.

The above sets forth one complete cycle of 35 operation of one cylinder. It will be understood of course, that the valve setting for the various cylinders is timed for each particular cylinder, and, since such cylinders work in sequence, it is manifest that some 40 cylinders will be drawing in gas while others are working. Since the piston displacement in the pumping chamber of each cylinder is greater than that required to adequately charge the working chamber in the same cylinder, it follows that the surplus portion 45 of the charge being compressed in each pumping chamber may be transferred to the manifold pipe 12 for use in other cylinders. In this way also a too heavy compression 50 and corresponding back pressure in the pumping cylinder is avoided. This also adds to the efficiency of the motor.

While in many respects considered from the standpoint of construction, my present 55 engine corresponds to that set forth in my previous Patent, No. 1,253,599 of January 15th, 1918, nevertheless, the present engine is distinctly different in that I provide means for transferring a substantial portion 60 of the gas from the pumping cylinder to the manifold instead of delivering substantially the entire compressed charge to said working chamber as I did in my former construction.

65 The importance of the invention should

not be measured by its apparent simplicity, since in fact the present invention results in producing an engine of much greater efficiency than that disclosed in my aforesaid patent.

70

What I claim is:

1. In an internal combustion engine, a plurality of cylinders, each cylinder having a working chamber and a pumping chamber, an inlet port leading into the working chamber of each cylinder, a gas supply pipe having a manifold connection with said cylinders, a piston in each cylinder, a portion of the piston arranged to reciprocate in the working chamber and another portion arranged to reciprocate in the pumping chamber, 75 a passage from the pumping chamber in each cylinder to the inlet of the working chamber in the same cylinder, said passage having a branch leading to said gas supply manifold, a single rotatable valve in said passage, said valve having a transverse passage therethrough, means for operating said valve to open communication between the pumping chamber and the working chamber 80 during a portion of the compression stroke to charge said working chamber, to then close communication to said working chamber, and to then open communication between said pumping chamber and said manifold for a substantial portion of the balance 85 of the same compression stroke to relieve the compression in said pumping cylinder.

2. In an internal combustion engine in combination, a gas supply pipe, a cylinder 100 having a working chamber, an inlet port at one end and an exhaust port at the other end thereof, a piston arranged to reciprocate therein and to control the exhaust port to open the same at the end of its working 105 stroke, means for introducing a combustible charge into the working chamber throughout a portion of the compression stroke of the piston therein and for transferring the balance of said charge into said gas supply 110 pipe throughout the balance of the compression stroke, said means comprising a pumping chamber of larger piston displacement 115 than the diameter of the working chamber, said piston having a pumping end working in said pumping chamber, a passage from said pumping chamber to the inlet of the working cylinder and a single rotatable valve in said passage operable to open and close the same, said valve having a transverse passage therethrough, operating to open said inlet passage throughout a portion 120 of the compression stroke of said piston and to close said inlet passage before said compression stroke has been completed, and thereafter open another passage to permit the balance of the charge in the pumping cylinder to be expelled therefrom and into the gas supply pipe during the balance of 125 said compression stroke, said valve operat- 130

ing to keep the inlet port closed throughout the power stroke and also during the period while exhaust port is open.

3. In an internal combustion engine, a plurality of cylinders, a fuel supply pipe having a manifold connection with the various cylinders, each cylinder including a working chamber and a pumping chamber, a valve chamber having passages communicating with said manifold, said working chamber and said pumping chamber, a single rotatable valve for controlling communication between the pumping chamber and said manifold and said working chamber respectively, said valve having a transverse passage therethrough with means for moving said valve whereby communication for the first part of the compression stroke will be opened from said pumping chamber to the working chamber, and during a substantial part of the balance of said stroke will be cut off from the working chamber and opened to said fuel supply pipe, whereby a portion of the charge being compressed in the pumping chamber will first be fed to the working chamber and the balance to said supply pipe for use in another cylinder.

4. In an internal combustion engine, a plurality of cylinders, each cylinder having a working chamber and a pumping chamber, an inlet port leading into the working chamber of each cylinder, a gas supply pipe having a manifold connection with said cylinders, a piston in each cylinder, a portion of the piston arranged to reciprocate in the working chamber and another portion arranged to reciprocate in the pumping chamber, a passage from the pumping chamber in each cylinder to the inlet of the working chamber in the same cylinder, said passage having a branch leading to said gas supply manifold, a single rotatable valve in said passage, said valve having a transverse passage therethrough, means for operating said valve to open communication between the pumping chamber and the working chamber during a portion of the compression stroke, and to then close communication to said working chamber and open communication between said pumping chamber and said manifold for a substantial portion of the balance of the same pumping stroke, and to continue said open communication with said gas supply pipe during the major portion of the suction stroke of the piston in said pumping chamber.

5. In an internal combustion engine, a plurality of cylinders, each cylinder having a working chamber and a pumping chamber, an inlet port leading into the working chamber of each cylinder, a gas supply manifold connected with the several cylinders, a piston in each cylinder having a portion ar-

ranged to reciprocate in the working chamber and another portion arranged to reciprocate in the pumping chamber, a valve chamber, a single rotary valve therein having a port transversely through the same, a passage from the pumping chamber to the wall of the valve chamber, two ports in the wall of said valve chamber in communication with different parts of said passage, an exhaust port adjacent the lower end of the working chamber, said exhaust port being opened and closed by said piston, means to rotate the valve to open communication between the pumping chamber and the working chamber on the compression stroke of the piston after the exhaust valve is closed, to close said communication before the piston reaches the end of said stroke and to open communication between the pumping chamber and the manifold during the balance of said stroke, maintaining said communication during the succeeding power stroke, whereby on each compression stroke of the piston a substantial portion of the gas in the pumping chamber will be transferred to the working chamber and another substantial portion thereof transferred to the manifold and whereby on the working stroke said pumping chamber will be fully charged.

6. In an internal combustion engine a cylinder, said cylinder having a working chamber and a pumping chamber, the diameter of the pumping chamber being greater than the diameter of the working chamber, a piston, one portion of which is adapted to fit in and reciprocate in the working chamber and another portion of which is adapted to fit in and reciprocate in the pumping chamber, a gas supply inlet having a passage leading to said pumping chamber, a valve chamber in said passage, an intake port leading from said valve chamber into the working chamber, an exhaust port in the wall of said working chamber at the opposite end from said intake port, a valve rotatable in said valve chamber, said valve operating to close said intake port and at the same time furnish communication between the gas supply inlet and the pumping chamber during the power stroke of the piston, and also operating to close the gas supply inlet and open communication between the pumping chamber and the working chamber during the major portion of the compression stroke of the piston to charge the working chamber, and to shut off said communication and place the pumping chamber in communication with the gas supply inlet during the last part of the same compression stroke to relieve excess compression in the pumping chamber at such time and to conserve fuel.

JOHN JOSEPH HOGAN.
